UNITED STATES PATENT OFFICE.

JEREMIAH C. FITZGERALD, OF KILBOURNE, WISCONSIN.

LITTER-CARRIER.

1,265,314.

Specification of Letters Patent.

Patented May 7, 1918.

Application filed June 23, 1917. Serial No. 176,587.

To all whom it may concern:

Be it known that I, JEREMIAH C. FITZGERALD, a citizen of the United States, and a resident of Kilbourne, in the county of 5 Columbia and State of Wisconsin, have invented certain new and useful Improvements in Litter-Carriers, of which the following is a specification.

This invention relates to that type of carriers or conveyers designed to travel on an elevated track, for the purpose of transporting litter, grain, coal, merchandise and the like from one point or place to another, and especially pertains to an automatic tripping 10 and unlocking mechanism with which the apparatus is equipped, certain co-operating parts of which, are mounted on the carriage and track, and it consists in certain peculiarities of the construction, novel arrangement and operation of the various parts 15 thereof as will be hereinafter more fully set forth and specifically claimed.

The principal object of the invention is to provide an overhead or elevated carrier of the above-named character, which is particularly intended for use in conveying litter and manure from the stalls or barns or stables out into the barnyard, or to a given or desired point, where it will be automatically 20 discharged of its load, which shall be simple and inexpensive in construction, strong, durable and efficient in operation, with its parts so made, arranged and operating as to adapt the carriage thereof for safe 25 travel back and forth on an elevated track which may have curves therein, and which may be made of a cable, wire-rod or a bar. Another object is to provide a box or receptacle forming a part of the carrier, which 30 shall be so mounted as to be locked in its upright position and automatically unlocked, to the end that, it may dump to either side desired. Still another object is to provide 35 a carrier or receptacle frame of novel construction which can be readily lowered to a suitable point to permit the box or receptacle to be loaded, and then easily raised to the desired height without disarrangement of the automatic tripping and unlocking 40 mechanism. Various other objects and advantages of the invention will be disclosed in the subjoined description and explanation.

In the accompanying drawing which 45 serves to illustrate an embodiment of the invention,

Figure 1, is a view in side elevation of the carrier, showing it mounted on a portion of an elevated track, and by continuous lines about the position the parts will occupy 50 when the box or receptacle is ready to be loaded, the suspending-devices for the receptacle frame being shortened for the convenience of illustration, and by dotted lines the position of parts of the tripping mechanism when in the act of being tripped to unlock the box, after it has been loaded, raised and conveyed to the point for dumping.

Fig. 2, is a cross-sectional view taken on 55 line 2—2 of Fig. 1, looking in the direction indicated by the arrows, but with the trip on the track omitted.

Like numerals of reference, refer to corresponding parts throughout the different 60 views of the drawing.

The elevated or over-head track is designated by the reference numeral 5 and in the present instance is shown as being made of a single rod or wire, yet it may be made of 65 a bar or cable and supported in the ordinary or any suitable manner. The track may have lateral curves to avoid obstacles or to direct the carrier in its travel in the proper direction. The carrier proper 70 comprises a carriage frame and a frame for the box or receptacle for the litter or other material to be transported, which latter frame is adjustably suspended from the carriage frame. The carriage or wheeled frame 75 consists of a pair of upright brackets 6, a pair of horizontally disposed bars or trucks 8, a rotary shaft 9, journal boxes or bearings 10 for said shaft and a horizontally disposed bar 10 which connects said journal boxes or 80 bearings at their lower ends. The upper end of each of the brackets or hangers 6 is provided with a flange or extension 10a projected toward the track 5 and each of said flanges or extensions has mounted thereon 85 one of the trucks or bars 7 which is swiveled to the flange or extension 10a by means of a suitable bolt 11 extended through the bar or truck 7 and the flange 10a of each of said brackets or hangers. Each of the bars or 90 trucks 7 is provided near each of its ends with a laterally extended stub-shaft 12 which shafts are projected in the same direction as the flanges 10a but over the track 5 as is clearly shown in Fig. 2 of the drawing. 95 Mounted on each of the stub shafts 12 is a sheave or wheel 13 each of which has a 100

- groove in its periphery for the reception of the upper surface of the elevated track. The lower ends of the brackets or hangers 6 are firmly secured to the upper portions of
- 5 the journal boxes or bearings 9 for the shaft 8, and by reference to Fig. 2 of the drawing, it will be seen that each of said bearings is laterally off-set from that portion thereof to which the hangers 6 are secured and also
- 10 that each of said bearings has a depending arm 14 to which the brace bar 10 is secured at or near its ends. The shaft 8 has mounted on one of its ends a sprocket or chain engaging wheel 15 which is provided on its
- 15 inner surface with ratchet teeth 16 to engage one end of a gravity pawl or dog 17 pivotally mounted on an extension 18 projected from that end of the bar 10 adjacent to the wheel 15 on which is mounted an endless chain 19 to be used for turning the aforesaid shaft. The pawl or dog 17 has one of its ends extended to engage by gravity the ratchet teeth 16 on the wheel 15 and is provided at its other end with a handled cord
- 20 or chain 20 to be used for releasing the dog 17 from said ratchet teeth. Pivotally mounted on the bar 10 at about the middle thereof is a trigger 21 which is extended at its lower portion longitudinally with respect to the
- 25 bar 10 and has at each of the ends of its lower part a depending forked extension 22, the prongs of each of said extensions being adapted to engage tripping levers carried by the frame for the box or receptacle, as
- 30 will be presently explained. The trigger 21 has extended upwardly therefrom an arm 23 which has at its upper portion an extension 24 projected under the track 5 and adapted to contact with one or the other
- 35 of the rounded ends 25 of a trip 26 which is suitably mounted on the track 5 at a suitable point where it is desired to cause the box or receptacle to tilt and dump its load. This trip may be secured to the track in any
- 40 suitable way so as to depend therefrom and so as to afford little or no obstruction to the passage of the sheaves or grooved wheels 13 of the carrier.

The frame or bail for the box or receptacle 27 is designated by the reference numeral 28 and as clearly shown in Figs. 1 and 2 of the drawing is substantially of an inverted U-shape, that is to say its upper portion is provided at each of its ends with

45 a downwardly extended member or prong 29 each of which is pivotally connected by means of a bolt 30 to one end of the box or receptacle 27, each end of which box is provided with a plate 31 having its upper edge curved and provided with a recess 32 to receive a projection 33 on the lower portion of a sliding collar or dog 34 which is mounted on each of the prongs or members 29 of the box carrying frame or bail. The

55 upper or horizontal portion of said frame

or bail has journaled thereon a pair of grooved pulleys 35 which by preference have their axles mounted below said portion of the frame. As shown in Fig. 1, the pulleys 35 are located one near each end of the 70 horizontal portion of the bail or frame 28 and said frame portion has mounted between each of the pulleys 35 and the member 29 of the frame adjacent thereto, a depending bracket 36 to the lower portion of each 75 of which is fulcrumed a tripping lever 37 each of which has its outer end deflected toward the prong or member 29 of the frame 28 adjacent thereto and provided with a hook 38 to engage the upper end of a flexible 80 connection 39, such as a chain, each of which is united at its lower end by means of a rod 40 to the upper portion of one of the collars or sliding members 34 on the prongs or members 29 of the box carrying 85 frame. Secured at one of its ends to the rotary shaft 8 near the middle portion thereof is a pair of cables or other flexible connections 41, one of which is extended beneath each of the pulleys 35, and each of 90 said connections 41 has its other end secured to the bar 10 near each of its ends.

From the foregoing and by reference to the drawings, it will be readily understood and clearly seen, that assuming the box or receptacle 27 to be in its lowered position ready to be loaded or filled, and it is desired to raise the receptacle and its frame in order that the tripping levers 37 may be acted on by the trigger 21, it is only necessary to 100 turn the wheel 15 in the proper direction to cause the cords or flexible connections 41 to be wound on the shaft 8, which operation will place the receptacle carrying frame in about the position shown by full lines in 105 Fig. 1 of the drawings where it will be held by the engagement of the pawl 17 with the ratchet teeth on the wheel 15 of said shaft. When thus positioned the carrier may be caused to travel on the track 5 until the extension 24 on the arm 23 of the trigger 21 strikes one end of the trip 26, which it will be understood is located on the track at a point where it is desired that the load carried by the receptacle shall be dumped and 110 disposed of. When the extension 24 on the trigger strikes the trip 26 it is apparent that said trigger will be tilted to about the position shown by dotted lines in Fig. 1, in which operation one of the forked extensions 115 22 on the trigger will engage one of the levers 37 thus causing both of said levers to be pressed downwardly at their inner ends and correspondingly raised at their outer ends thereby disengaging the bolts or projections 33 from the recesses 32 of the plates 31 on the ends of the receptacle when the latter will automatically tilt on its pivots and discharge its load. To lower the receptacle, it is only necessary to raise the pawl 120

125 130

17 by pulling down on the handle cord chain
20 when it is obvious that the weight of the
receptacle and its frame will cause the shaft
8 to rotate and permit the connections 41
5 to be unwound therefrom. The inner ends
of the levers 37 overlap each other and one
of said levers is provided with a longitudi-
nal slot 42 to receive a pin 43 on the other
of said levers, which arrangement will per-
10 mit of the downward movement of the same
as is apparent.

Having thus fully described my invention,
what I claim as new and desire to secure by
Letters Patent is—

15 1. In a litter-carrier, the combination with
an elevated track and a trip depending there-
from, of a carriage-frame mounted to travel
upon the track and extending below the
same, another or receptacle-carrying frame
20 adjustably suspended from the lower por-
tion of the first named frame and including
a bail, a receptacle tiltably mounted on the
lower portion of said bail and carried there-
by, a lock at the end of the receptacle, a
25 trigger pivotally mounted on the carriage-
frame and extended upwardly to strike said
trip, a lever suitably fulcrumed on said bail
and extended into the path of said trigger,
and a connection uniting said lever and the
30 bolt of the lock to unlock the receptacle.

2. In a litter-carrier, the combination with
an elevated track and a trip depending there-
from, of a carriage-frame mounted to travel
upon the track and extending below the
35 same, another or receptacle-carrying frame
including a bail adjustably suspended from
the first named frame, a receptacle tiltably
mounted on the lower portion of said bail,
a lock at the end of the receptacle, a trigger
40 pivotally mounted on the carriage-frame
and extended upwardly to strike said trip,
said trigger having at its lower portion a
pair of spaced apart extensions, a lever suit-
ably fulcrumed on said bail and so located
45 that when the bail is raised to its highest
position, one of said extensions will rest on
top of said lever and be so positioned as to
be depressed by said extension when the

trigger is tilted, and a connection uniting
said lever and the bolt of the lock to unlock 50
the receptacle when the trigger is tilted by
contact with said trip.

3. In a litter-carrier, the combination with
an elevated track and a trip depending there-
from, of a carriage-frame mounted to travel 55
upon the track and extending below the
same, another or receptacle-carrying frame
adjustably suspended from the first named
frame and including a bail, a receptacle tilt-
ably mounted on the lower portion of said 60
bail and carried thereby, a lock at each end
of the receptacle, a trigger pivotally mount-
ed on the first named frame and extended
upwardly to strike said trip, said trigger
having at its lower portion a pair of spaced 65
apart extensions, a pair of levers disposed
longitudinally with respect to the bail and
fulcrumed thereon and having their adj-
acent portions loosely connected together and
located beneath the trigger, connections unit- 70
ing said levers to the bolts of the locks to
unlock the receptacle when the trigger is
tilted by contact with said trip.

4. In a litter-carrier, the combination with
a pair of wheeled hangers adapted to travel 75
on an elevated track, of a winding shaft
horizontally and longitudinally journaled on
said hangers, a bar uniting the hangers, an
upwardly extending trigger pivotally mount-
ed on said bar and having on its lower por- 80
tion a pair of spaced apart receiving sockets,
a bail adjustably suspended from the wind-
ing shaft and said bar, a receptacle tiltably
mounted on the bail, a lever fulcrumed on
the bail and so arranged that when the bail 85
is raised to a suitable position said lever will
contact with one of said sockets on the trig-
ger to depress one end and raise the other
end thereof by the tilting action of the trig-
ger.
